UNITED STATES PATENT OFFICE.

HARRY A. STURNI, OF NEW YORK, N. Y.

DUMPING FREIGHT-CAR.

1,207,445.

Specification of Letters Patent.

Patented Dec. 5, 1916.

Application filed October 27, 1915. Serial No. 58,141.

To all whom it may concern:

Be it known that I, HARRY A. STURNI, a citizen of the United States and a resident of the city of New York, borough of the Bronx, in the county of Bronx and State of New York, have invented a new and Improved Dumping Freight-Car, of which the following is a full, clear, and exact description.

10 This invention relates to railway rolling stock and has particular reference to dumping freight cars.

Among the objects of the invention is to improve that class of freight cars provided with movable bottoms for discharging the contents when desired.

More definitely stated, the invention contemplates the provision of a car bottom normally horizontal in closed position but adapted to be dropped or lowered along either side for discharging the contents of the car laterally at such side.

A further object of the invention is to provide supporting or controlling means for the sides of the bottom of such a nature that when either side is lowered the opposite side support constitutes a fulcrum or hinge portion for that side which remains elevated and approximately in its normal position.

30 A still further object is to provide a dumping freight car having hinged side doors, one on each side of the car, the door on the side where the material is discharged being adapted to swing freely outwardly under the force of the moving material while the door on the opposite side is caused positively by movement of the car bottom to move inwardly slightly to facilitate the delivery of the material.

40 With the foregoing and other objects in view, the invention consists in the arrangement and combination of parts hereinafter described and claimed, and while the invention is not restricted to the exact details of construction disclosed herein, still for the purpose of illustrating a practical embodiment thereof reference is had to the accompanying drawings, in which like reference characters designate the same parts in the several views, and in which—

Figure 1 is a side elevation in diagram of a freight car made in accordance with

this invention; Fig. 2 is an end view of the same; Fig. 3 is a vertical transverse section substantially on the line 3—3 of Fig. 1, but on a larger scale; Fig. 4 is a view similar to Fig. 3 but indicating the parts in dumping position; Fig. 5 is a vertical longitudinal sectional detail on the line 5—5 of Fig. 3; Fig. 6 is a vertical transverse sectional view on the line 6—6 of Fig. 7, indicating the bottom controlling devices in the position assumed by them at the time the bottom is restored to normal position but not yet locked; Fig. 7 is a vertical sectional detail at right angles to Fig. 6 and on the line 7—7 thereof; Fig. 8 is a horizontal sectional detail on the line 8—8 of Fig. 6; and Fig. 9 is a vertical sectional detail of one of the buffers.

The general construction of the car body 10 and the trucks 11 may be of a standard nature, and except as hereinafter specified I do not wish to be limited with respect to general structural details. The car body 10 is provided at each end with a sloping stationary floor section 12, the lower or inner end of which registers with the movable bottom 13 when in normal position. Any material, therefore, that may be supported upon the ends of the car will be directed downwardly toward the middle portion of the car and thus discharged when the car is being unloaded.

The movable floor 13 may be regarded as a single plate for the purpose of this consideration, the same being mounted in any suitable manner upon transverse girders 14 and provided along its lateral edges with angle plates 15. As shown in Figs. 3 and 4, the plates 15 are each arranged with a vertical flange on the outside and a horizontal flange at the bottom, and at any suitable points along each of the plates are provided a plurality of holes or openings 16 between the vertical flange and the adjacent edge of the floor plate 13.

As above premised, at each side of the car body 10 is a door 17 substantially co-extensive longitudinally of the car with the movable floor 13 and hinged at its upper edge at 18 so as to swing outwardly freely when the car is being dumped. Each door 17 in normal closed position is inclined in

wardly slightly at its bottom from the vertical, being so held by means of a series of upright posts 19 along the outer side of the door. The lower ends of the posts 19 extend below the lower edge of the door and have their outer corners rounded off as indicated at 20. These lower ends of the door posts are received in and through the openings 16 above described, whereby the doors are locked shut when the bottom is closed. Each door hangs in substantially vertical position when released from the bottom and the material has been discharged from the car, as shown at the left hand side of Fig. 4. The rounding of the corners at 20 insures, however, that the vertical flange of the adjacent plate 15 will engage the posts 19 and cause the door to be moved inwardly slightly at its bottom into normal closed position when the floor is elevated to its normal position.

The movable floor is supported on a series of trusses 21 each comprising a pair of divergent legs extending downwardly and outwardly from the longitudinal central portion of the structure, the point or apex portion of each truss freely spanning the main longitudinal girder 22 of the rigid bottom frame. This frame also includes the side channels 23 and 24, together with such transverse members 25 as may be required. Both sides of the bottom are independently supported by devices mounted upon the stationary rigid frame just referred to, and either side of the bottom may be manipulated independently of the other.

I will now describe specifically the controlling mechanism for either side of the car bottom, and such description will be understood as being applicable to the other side. The power shaft 26 is journaled longitudinally of the frame closely adjacent the inner side of the channel beam and projects from both ends of the car. A series of pinions 27 are fixed to the shaft 26, and these pinions 27 mesh with a corresponding number of arc-shaped racks 28 carried by rigid supports 29 constituting a part of the frame. The racks 28 are located on the inner side of the pinions or between the pinions and the longitudinal center of the car. The shaft 26 may be rotated through any source of power, the same being typified by a hand lever 30 connected to a ratchet wheel 31 at either end of the shaft. A pawl 32 co-operates with the ratchet wheel and serves to hold the shaft from such rotation as would permit the racks to move downwardly. These pawls and ratchets are useful particularly during the hoisting of the movable car floor 13.

A rock shaft 33 is located below and closely adjacent and parallel to the power shaft 26 and likewise extends the full length

of the car. At either end of the rock shaft 33 is secured a socket member 34 whereby the said shaft may be rotated as by means of the same lever 30. A series of lugs 35 of substantially semi-cylindrical form are secured along the rock shaft 33 preferably one for each pinion 27. The rock shaft 33 is located inwardly slightly from the vertical plane of the power shaft 26 and is adapted to be rotated through substantially a half rotation so as to swing the lugs either inwardly or outwardly. When the lugs are swung so as to be on the inner side of the rock shaft, they are adapted to fit into correspondingly shaped bearing sockets 36 secured to the lower ends of the rack supports 29 and just below the ends of the racks. Each of these bearing sockets is so disposed as to have its concave side or active surface directed outwardly, and such active face embraces a sufficient portion of the lug 35 as to constitute with the lug and rock shaft a primary support for that side of the car bottom. In other words, while the pinions 27 are designed primarily for hoisting the bottom, the carrying load is designed to be supported normally upon the lugs. Antifriction rollers 38 may be employed to relieve the friction at any of the bearing points of the structure, if desired. At this stage it will be noted that the racks 28 on either side of the car are curved upon arcs whose centers coincide with the axis of the rock shaft 33 upon the opposite side of the car. It follows, therefore, that when the lugs 35 are withdrawn from the bearing seats 36 by the swinging of the rock shaft to which they are connected around its axis through substantially a half rotation, the pawls 32 having been released from the ratchet wheels 31, that side of the car bottom will swing downwardly around the axis of the opposite shaft 33 as a center. During this movement the pinions 27 constitute positive means to prevent the lateral displacement of the bearing sockets 36 from the lugs upon the opposite side and around which the bottom moves as a whole.

When the bottom 13 swings downwardly on one side the plate 15 thereof is adapted to co-operate with a suitable number of buffers, shown in detail in Fig. 9, and each including a plunger 37 reciprocating vertically in a socket member 38 and including a cushioning device of any suitable nature indicated by a spring 39. The socket members are rigidly secured to the channel beams 23 and 24, whereby the impact due to the sudden droppage of the bottom will be relieved from the car structure.

From what has been stated above, when one side of the bottom is dropped, the adjacent door will be released therefrom and be free to swing outwardly under the force of

gravity and the pressure of the material being dumped. At the same time the door on the opposite side of the car will be forced inwardly slightly due to the interlocking engagement between the lower ends of the posts 19 thereof and the angle plate 15, it being noted that the line of engagement of the then closed door and the car bottom is located at a distance materially above the then supporting rock shaft and lugs. In other words, the action of the bottom and supporting means is similar to that of a bell crank, the weight of the material upon the bottom and gliding downwardly thereon serving to cause the short arm of the bell crank to move the then closed door inwardly, as shown at the right hand side of Fig. 4, and thereby the discharge of the material from the car is facilitated.

To restore the bottom to normal position, power is applied to the power shaft on the open side of the car, the pawls and ratchets coöperating to prevent reverse rotation of such shaft until the bottom is fully lifted and in position to be locked and positively supported by the lugs 35 after they are swung around into locking position as shown in Fig. 3. The rock shaft 33 is well mounted and of sufficient weight to bear the strains imposed upon it through the lugs, but because of the antifriction rollers 36' the operator has no difficulty whatever in swinging the lugs out of locking and supporting position to permit the car bottom to swing downwardly, as above described, on either side.

I claim:—

1. In a dumping freight car, a rigid bottom, a series of rigid members secured at their upper ends to the rigid bottom and extending downwardly therefrom adjacent the opposite sides of said bottom, rotary means coöperating with said rigid members to elevate the bottom to closing position, and other rotary means adjacent the first mentioned rotary means coöperating with said rigid members to hold the bottom in closed position.

2. In a dumping freight car, the combination with a rigid frame and a car body supported thereon, of a movable bottom for the car body, rotary devices journaled in the frame adjacent the opposite sides thereof, arc shaped racks connected to the sides of the bottom and extending downwardly therefrom into coöperation with said rotary members to control the position of said bottom, said rotary means and racks being duplicated on opposite sides of the car to provide for the downward tilting movement of the bottom for dumping on either side of the car, a bearing socket connected to the lower end of each rack and curved reversely to the rack, the center of curvature of the socket

coinciding with the center of movement of the opposite edge of the bottom, and a rotary lug located normally in said socket to sustain the adjacent edge of the bottom.

3. In a dumping freight car, the combination with a rigid frame and a car body supported thereon, of a rigid movable bottom for the body above the frame, arc-shaped rigid supports connected to the opposite sides of the bottom and extending downwardly therefrom with their convexities opposite each other, bracing means connected to the lower ends of said supports to maintain them in fixed position with respect to the bottom, rotary controlling means journaled in the frame and coöperating with said rigid supports to control the position of the bottom, said rotary controlling means providing on either side of the car a substantially fixed support for that side of the bottom and providing for the rigid support on the opposite side of the car to move downwardly in an arc of a circle concentric with the stationary controlling means upon the releasing of the controlling means on the opening side of the car.

4. In a dumping freight car, the combination with a rigid frame and a car body supported above the same, of a bottom movably arranged between the body and the frame, a series of racks connected at their upper ends of the bottom and extending downwardly therefrom on opposite sides of the car, bracing and supporting means coöperating with said racks to hold them in rigid position with respect to the bottom, a series of power pinions meshing with the respective racks for elevating the bottom to closed position, a series of lugs journaled in the frame adjacent the pinions, said supporting means being provided with arc-shaped bearings adapted to receive the lugs for the main supporting means for the bottom, and means to rotate all of the lugs on either side of the car simultaneously to permit that side of the bottom to swing downwardly around the other series of lugs as an axis.

5. In a dumping freight car, the combination with a body having an open bottom and a movable door on each side of the body, each door being hinged along its upper edge and adapted to swing inwardly and outwardly with respect to the body at its lower edge, of a bottom movable upwardly into interlocking engagement with the lower edges of both doors in closed position, and means controlling the position of the bottom and providing for the bottom to swing open downwardly at either side, permitting the body door on that side to swing outwardly and causing the body door on the closed side to swing inwardly.

6. In a dumping freight car, the combination with a car body having a movable side

- member and an opening in its bottom, of a bottom closure for said body opening, means to control the movement and position of the bottom closure causing one side thereof to interlock with said movable side member and providing for the downward opening movement of the bottom opposite said side

member and thereby causing said movable member to swing inwardly to facilitate the discharge of material from the car body.
